Patented Jan. 23, 1968

209,972

DOG FEEDER

Furman E. Ott, Rte. 3, Laurens, S.C. 29360

Filed Apr. 20, 1967, Ser. No. 6,771

Term of patent 14 years

(Cl. D30—15)

Fig. 1.

Fig. 2.

Fig. 3.

FIGURE 1 is a front perspective view of the dog feeder,

FIGURE 2 is a front perspective view of the dog feeder showing the interior thereof, and

FIGURE 3 is a rear perspective view of the dog feeder further illustrating my new design.

I claim:

The ornamental design for a dog feeder, substantially as shown.
